UNITED STATES PATENT OFFICE

2,506,682

GUIDING MEANS FOR ROLLING MILLS
AND THE LIKE

Sven Erik Malte Norlindh, Hallefors, Sweden

Application October 4, 1944, Serial No. 557,143
In Sweden February 16, 1943Section 1, Public Law 690, August 8, 1946
Patent expires February 16, 1963

7 Claims. (Cl. 80—51)

1

The present invention relates to guiding mechanism for rolling mills and the like and particularly to constructions in which rollers are used as the guiding members.

Objects of the invention are to provide guiding mechanism including guide rollers carried by flat spring members that are supported in a guide casing for rocking movement about axes parallel to the guide roller axes, and that are pressed toward the work by pressure screws that engage the spring members between their supported ends and their guide roller ends. An object is to provide guiding mechanism including a guide box and guiding rollers, spring members carrying the guide rollers, and a casing in which the guide box and the spring members are supported independently of each other.

These and other objects and advantages of the invention will be apparent from the following specification when taken with the accompanying drawings in which:

Fig. 1 is a plan view of guiding mechanism embodying the invention;

Figs. 2 and 3 are sectional views taken on lines II—II and III—III of Fig. 1, respectively;

Fig. 4 is a longitudinal section through another embodiment of the invention as seen on the plane of line IV—IV of Fig. 5;

Fig. 5 is a section taken on the plane of line V—V of Fig. 6;

Fig. 6 is a transverse section taken on the plane of line VI—VI of Fig. 5;

Fig. 7 is a schematic view illustrating movement of the guide rollers;

Fig. 8 is a longitudinal section through another embodiment of the invention as taken on line VIII—VIII of Fig. 9;

Fig. 9 is a section on line IX—IX of Fig. 10; and

Fig. 10 is a transverse section on line X—X of Fig. 9.

In the drawings, the reference numeral 1 identifies the base or casing that supports the several elements of the guide mechanism and that in turn is supported in the rolling mill in any known or desired manner that forms no part of the present invention. The holders for the guide rollers each comprises a flat spring member 2 having a bearing sleeve 2d welded to one end and a roller head 3 welded to the other end. The bearing sleeves fit over shafts 2a that are welded to the casing 1, and the holders are retained on the shafts by screws 2c that are threaded into the shafts and seat on washers 2b. Shield plates 2e are preferably mounted between the sleeve 2d

and the roller head 3 of each holder, and spaced from the springs 2, to protect the latter from heat radiation in the hot rolling of bars and rods. The guide rollers 4 are mounted on the roller heads 3 by ball bearings 5 and shafts 6. A pair of screws 14 are threaded into wall portions 1a at each side of the casing 1 to adjust the spacing of the rollers 4 to the size of the bars or other stock to be rolled.

10 The thickness of the flat spring members 2 will depend upon the material to be handled and other design requirements in particular cases, the essential conditions contemplated by the invention being that the roller holders are resilient and are mounted on the casing 1 for angular or rocking movement, and that the screws 14 apply pressure to the intermediate section of the resilient holders to adjust the normal spacing of the rollers 4 and to insure adequate pressure of the rollers 4 upon the work piece. As indicated graphically in Fig. 7, the resilient holders provide an automatic adjustment of the spacing of the rollers 4 to meet different operating conditions such as, for example, that of a square rod or work piece 18 20 that should run "flat" through rolls 17 (indicated by arcuate lines 17, Fig. 2) but that approaches the rollers 4 on the diagonal. The spring members yield to permit the movement of the bar into the rollers 4 and the resultant high pressure exerted on the bar 18 by the rollers 4 will quickly effect a partial rotation of the work piece 18 into a stable position with opposite sides flat against the rollers 4.

25 The rollers 4 of the embodiment shown in Figs. 1—3 are cylindrical, and this form of the invention is adapted for use with flat or approximately flat stock that has opposed plane surfaces. Guide boxes and/or the vertically arranged set of rollers of the so-called "universal rolling mills" are eliminated by the resilient mounting of the rollers 4 on the holders that include the flat spring members 2.

30 It is to be noted that the described construction of the roller holders by welding a bearing sleeve 2d and a roller head 3 results in considerable manufacturing economy as the parts 2d and 3 may be of relatively soft iron or steel that machines easily.

In the embodiment illustrated in Figs. 4 to 6, 35 the casing 1' is of rectangular frame form, as viewed in cross-section, and a guide box 8 is mounted within the casing between filler blocks 9, 10 that are pressed toward each other by screws 13. The lower block 10 is secured to the casing 1' by screws 16a, and both blocks have

side flanges 8a that insure the desired lateral positioning of the guide box. Forward movement of the guide box is prevented by a lug or stop 11 that may be an integral part of the casing 1'. The flat springs 2 are arranged between the guide box 8 and the side walls of the casing 1', the springs being supported on a rocker 12 to which they are clamped by pressure screws 15 that are threaded through the upper wall of the casing. Each spring 2 has rounded bearing projections a at its upper and lower edges that are drawn into engagement with the casing walls by an anchoring screw 16. The rocker 12 is well in advance of the screws 16 on which the springs 2 pivot when the roller heads 3 are vertically adjusted with respect to each other by means of the screws 15. The roller heads 3 and rollers 4 are adjusted towards each other by screws 14 that are located between the rounded bearings a of the springs and the roller heads 3. The anchor screws 16 are located adjacent the bearings a and at the side thereof towards the adjusting screws 14, whereby the roller holders are held apart by tightening the screws 16. This mounting is particularly advantageous in high speed rolling as it prevents the rollers from swinging into the path of the material being rolled. As shown in Fig. 6, the bearing projections a provide a space between the springs 2 and the adjacent side walls of the casing 1', and the screws 16 are drawn down to flex the springs transversely to develop such pressures at the adjusting screws 14 that the latter are held locked against inadvertent rotation.

The embodiment shown in Figs. 8 to 10 differs from the guide mechanism of Figs. 4 to 6 in that the points of attachment and the points of adjustment of the roller holders are reversed. In the Figs. 4 to 6 construction, the ends of the springs 2 are supported on the casing for rocking movement on the bearing projections a and for angular adjustment about the axes of the anchor screws 16, and these adjustments are effected by the screws 14 and 15, respectively, that are located at intermediate points on the casing 1'.

As shown in Figs. 8 to 10, the guide box 8 and associated elements are substantially the same as previously described, but the rocker 12 and vertical adjusting screws 15 are at the entrance end of the casing 1', and the anchor screws 16 extend through the casing 1' at the advance points to draw the springs 2 down upon the rounded bearing projections, i.e. support screws 16a mounted in the walls of the casing 1', after the rollers 4 have been adjusted as desired by screws 14 that extend through the springs 2 to seat upon the guide box 8.

It is to be noted that the guide box 8 shields the springs 2 from radiation when rolling hot bars and rods, thus making it unnecessary to provide separate shield members similar to the shield plates 2e of Fig. 1.

The invention is not limited to the use of but two guide rollers or to the particular constructions herein shown and described as various changes may be made in the parts, their relative arrangements and mountings without departing from the spirit of my invention as set forth in the following claims:

I claim:

1. Bar stock guiding mechanism for rolling

rolls comprising a supporting base, a pair of resilient members one at each side of the path for the bar, a guide anti-friction roller carried by the free outer end portion of each of said members the periphery of the roller ahead of the rolling mill reaching outside said end portion which constitutes a roller head integral with the resilient member, means mounting said members on said base for angular adjustment independent of each other about axes parallel to the axes of said rollers, and adjusting screws engaging said resilient members at points spaced from said mounting means to determine the normal spacing of said rollers from each other.

2. Guiding mechanism as recited in claim 1, wherein said mounting means comprises shafts secured to said supporting base and bearing sleeves welded to said resilient members.

3. Guiding mechanism as recited in claim 1, wherein said supporting base comprises a casing having side walls; and said mounting means comprises rounded bearing projections on said resilient members, and anchor screws for drawing said resilient members towards the respective side walls to seat said bearing projections thereon.

4. Guiding means for rolling mills comprising a pair of guide rollers, flat spring members carrying said rollers in roller heads constituting parts of the resilient members, the peripheries of the rollers ahead of the rolling mill reaching outside the roller heads, a casing within which said spring members are positioned, bearing projections supporting said spring members rocking about axes parallel to the axes of said rollers, adjusting screws engaging said spring members at points spaced from said bearing projections to rock said spring members to determine the normal spacing of said rollers, and anchor screws drawing said spring members into engagement with said adjusting screws.

5. Guiding means as recited in claim 4, wherein said bearing projections are on said spring members.

6. Guiding means as recited in claim 4, wherein said bearing projections are at the entrance end of said spring members, and said adjusting screws engage intermediate points on said spring members.

7. Bar stock guiding mechanism as defined in claim 1 and which further includes a heat shield interposed between each of said resilient members and the bar stock when passed through the mechanism.

SVEN ERIK MALTE NORLINDH.
